UNITED STATES PATENT OFFICE.

ALBERT A. BRINKMAN, OF ST. PAUL, MINNESOTA, ASSIGNOR OF ONE-HALF TO ELODIE M. HUYGENS, OF ST. PAUL, MINNESOTA.

BOXING TOY.

Application filed September 17, 1928. Serial No. 306,391.

My invention relates to a boxing toy and the main object is to provide an attractive, realistic and novel toy of said class in which the movements of a pair of real boxers engaged in a boxing match are very closely duplicated or imitated and governed by certain manipulations of control means, as herein-after described and illustrated in the accompanying drawings, in which,—

10 Fig. 1 is a side elevation of my toy with one side of its base removed to reveal certain details.

15 Fig. 2 is an approximately vertical cross-sectional detail about as one line 2—2 in Fig. 1 and in enlarged scale.

20 Fig. 3 is an elongated sectional view as on line 3—3 in Fig. 1, being enlarged in scale to reveal certain interior mechanisms of the head part of either of the two fighting figures of the device.

25 Fig. 4 is an enlarged vertical elevation of the lower part of either of the fighting figures looking as from a central vertical plane toward one of the legs.

30 Referring to the drawings by reference numerals and letters, A and B designate two fighting figures, normally of course upright and mounted on the top C² of a box-like base C having end walls C³, side walls C⁴ and bottom C⁵. Said figures have each a head 5 preferably of hollow cast construction and the neck part of which is connected to the body by suitable flexible means such as a piece of stiff but resilient rubber 6. The body of each 35 fighting figure is also hollow cast construction down to the knees 7 at which place there is a horizontal pivot pin 8 in each joint connecting the body to the lower leg or foot portion 9. One foot of each figure is pivotally 40 fixed to the base by a vertical pin 10 projecting down through the box-top C² and having a head at its lower extremity.

45 11 (Fig. 2) is a helical coil spring about each pin 10 below base part C² and suitably fixed to the base and to the head part of the pin in such manner as to hold the leg part 9 upright and so that the figure it is supporting normally faces the other counterpart figure. When either figure is knocked part way round 50 on its, pivot by a blow, the spring automatically restores the figure to its original position.

55 12 in Fig. 4 is an upright single spring bar fixed as at 13 to the lower leg part 9 and its upper part engaging between two pins

14 on the adjacent thigh part of the same leg. Such spring is normally vertical and holds the body of the fighting figure normally vertical above the knee joint. If one figure should receive a blow from the other fighting figure which throws its body part back, the said body part will of course spring back as to dotted line position in Fig. 4 momentarily, the spring 12 yielding but immediately restoring the figure to upright position.

I will now describe the arm manipulating means for the figures, a description of one figure only being necessary as they are counterparts, and certain features in the head part of each figure.

15 15 is a horizontal transverse aperture through each figure at its shoulder, in the opposite end parts of which is pivotally mounted vertically a pair of rollers 16. 17 is a dimetrical pin rotatably retained in each roller, and exteriorly of the roller the upper end of an arm 18 is mounted while the inner end of said pin comprises lever 17A to which is attached a manipulating cord 19 extending downwardly within the body and thence into the hollow base to manually operated means for raising and lowering the arms.

20 Said means comprises a shaft 23 extending longitudinally under the cover C² and journaled in the end walls C³ protruding from one of the latter where it carries any suitable type of finger-operated means such as a button or knob 20 (see Fig. 1) which is engaged to oscillate the shaft 23. 21 is a beam lever for each figure and directly below it, a cord 19 extending down from an arm lever 17A to each end of this lever. It is now clear that oscillation of knob 20 causes the arms 18 of each figure to raise or lower on their respective pins 17, each arm of course being normally hanging down at the side of the figure when its lever 17A is directed upwardly and said arm being raised by the downward movement of lever 17A when cord 19 is pulled downwardly by the action of the beam lever arm 21 to which it is attached. The mechanical action just described gives a realistic arm movement for raising and lowering the arms of each figure and stimulating a punching action of a real fighter swinging his arms in a boxing contest. I also provide further arm swinging means consisting of a cord 31C for each arm roller member 16, each cord passed horizontally

part way around each roller from a pin 33 (Fig. 2) thence inwardly to a central fixed upright guide roller 34 thence rearwardly toward the back of the figure to a horizontally fixed roller of bar 35, (Fig. 2) thence downwardly within the body, to and through the top of base C. There is of course thus a pair of cords 32 within each fighting figure the lower ends of said cords attached to the following manipulating means.

25 are a pair of longitudinally spaced disc belt-wheels or pulleys, within base C, and 26 is an intermediate drive pulley, all mounted in a frame 27 fixed on floor C5 of the base 15 (as in Figs. 1 and 2) on shafts 28 and 29 respectively.

30 is a belt or equivalent engaging under pulley 26, thence passed upwardly and outwardly over discs 25 and under the latter. 20 Shaft 29 is provided with a crank 29C exteriorly of the base and turning of the latter causes discs 25 to rotate simultaneously. The latter have each a pair of auxiliary discs 31, one on each end of its shaft 28, each said 25 disc 31 having a crank pin 32 to which is attached the lower end of a cord 31C. It is understood that there is one disc 25 and its associated parts, as described, under each fighting figure. Manipulation of crank 25C 30 causes discs 25 and 31 to rotate and the crank pins 32 pulling or releasing their pull on cords 31C causes the arms 18 to be swung around horizontally as the rollers 16 are oscillated. Now it will be understood that the 35 upward swinging of arms 18 by means of the levers 17A manipulated by oscillation of knob 20 and simultaneous swinging of the arm pivot rollers 16 creates a lift like action as compared to real boxers engaged in a boxing match.

It is well known in boxing circles that fighters often acquire discolored eyes during a boxing match. I have also provided for an imitation of this in the use of my boxing 45 toy. The head of either combatant (as on figure A in Fig. 1) may be at any time violently struck by an arm of the other fighter, causing the said head to be tilted back suddenly as illustrated. The tilting is only 50 momentary and the rubber mounting 6 of the head permits of it but instantly pulls the head back to normal position.

Each head of my device being hollow, as described, I provide two eye-apertures 36 55 therein, one at each side. 37 is a transverse shaft fixed in opposite side walls of the head. On said shaft 37 I mount a sleeve 38 with a fixed central depending counterweight 39. Forward of shaft 37 the sleeve 38 is provided 60 with two discs 40, one adjacent each eye aperture 36 and on the outer face of each disc is painted or otherwise represented, the pupil 41 of the eye and exposed in said aperture when the head is in normal position. Adjacent the pupil 41, the disc is painted a dark 65

color, as area 42 in Fig. 3 when the head is violently forced back, counterweight 39 swings away from normal hanging position as to dotted position shown dotted in Fig. 3, swinging on pivot shaft 37 and the dark 70 colored areas 42 of the discs 40 are swung to be exposed in the eye apertures, being retained in said position by a friction arm 43 with a depressed part 43A being sprung into a notch 38N in the hub 38H of sleeve 38 by 75 the bearing down action of a suitable spring 44 fixed at 45 in the rear wall of the head, said arm 43 being pivoted below said spring on a pin 46 in an aperture 5A in the rear part 80 of the head. Outwardly of the said pin 46 arm 43 is extended to form a short arm 43A which may be pressed down to disengage arm 43 from notch 38N to allow the weight 39 to drop to normal position, when the pupil 41 of the eye is again exposed in its normal 85 position.

In the foregoing description I have fully disclosed my invention embodying its preferred construction as disclosed in the drawings. It is obvious that a number of variations of details might be incorporated in the assembly of major and minor parts without departing from the scope and spirit of my invention.

For example it may be necessary to include a retrieving spring (not shown) for each arm roller 16 to keep a taut condition of its cord 31C. In the present instance however it has been found that the arms 18 can be so shaped where they enter the side 100 apertures 15 that the normal hanging position and weight of any arm causes its roller 16 to come to a certain position always providing sufficient tautness of its cord 31C. Also, in an inexpensive form of my device 105 the feet of the figures may be fixed permanent and further the entire figure may be rigid, omitting the yieldable self-adjusting knee joint and spring means described.

I claim:

1. In a boxing toy having a hollow base and two figures mounted thereon in simulation of two boxers facing each other, each figure mounted with a leg secured to the top of said base on a spring actuated pin normally, holding the figure in position to face the other figure, a knee joint in each leg, each figure comprising a hollow integral body and thighs the latter pivoted at said knee joints, a head mounted between the shoulders of each figure on a yielding, elastic element, an arm pivotally mounted in the body at each shoulder to be swung in vertical plane and further pivot means for each arm providing horizontal swinging of same, and arm manipulating means comprising cords operatively connected to said vertical and horizontally oscillatable arm means and extending downwardly through each figure to the interior of said base and further manually op- 110 115 120 125 130

erated means mounted in said base for selectively pulling and releasing said cords.

2. The structure specified in claim 1, in which the head of each figure is hollow and provided with eye apertures, a transverse shaft mounted in each head rearward of said eye apertures, a plate fixed on said shaft and oscillatable inwardly of and past each said aperture, a pendulum on said shaft, and a representation of a normal eye on each plate and exposed in said aperture when the head is normally upright, a colored area on each plate arranged to be oscillated into exposed position in each said aperture when the head is tilted beyond a normal upright position.

3. The structure specified in claim 1, in which the head of each figure is hollow and provided with eye apertures, a transverse shaft mounted in each head rearward of said eye apertures, a plate fixed on said shaft and oscillatable inwardly of and past each said aperture, a pendulum on said shaft, and a representation of a normal eye on each plate and exposed in said aperture when the head is normally upright, a colored area on each plate arranged to be oscillated into exposed position in each said aperture when the head is tilted beyond a normal upright position, and means within each head adapted to yieldably engage and hold said eye plates in position with their colored areas exposed and including a spring lever arm pivoted in the rear part of the head and having one arm exposed outwardly of the head to release the arm as described.

4. The structure specified in claim 1, in which said manually operated arm control

cord means in the base comprises a main drive wheel and two driven wheels, a pair of crank pins fixed on each of the latter and connected one to each of the horizontal arm swinging cords of the figure above it, a crank for rotating said driven wheels, simultaneously; an oscillatable shaft within the base with suitable finger engaging means exteriorly thereof, a beam lever fixed on said shaft below each figure and one of said cords manipulating the arm raising means attached to an end of said beam lever, substantially as shown and described.

5. The structure specified in claim 1 in which the pin of the mounted leg of each figure extends below the top of the base a retrieving coil spring about said pin with one end fixed to said base top and the other end to the pin to bring the figure back to a predetermined position after it had been swung away from such position.

6. The structure specified in claim 1 in which the pin of the mounted leg of each figure extends below the top of the base a retrieving coil spring about said pin with one end fixed to said base top and the other end to the pin to bring the figure back to a predetermined position after it has been swung away from such position, and a yielding, elongated stiff spring element fixed below each said knee joint and extending upwardly with its free end, means fixed on the adjacent thigh part of the figure slidably engaging said spring for the purpose described.

In testimony whereof I affix my signature.

ALBERT A. BRINKMAN.
